[57] CLAIM

The ornamental design for a shoulder support for surgical table, as shown and described.

DESCRIPTION

FIG. 1 is a perspective view of a shoulder support for surgical table, showing my new design.

FIG. 2 is a front elevational view thereof.

FIG. 3 is a right-side elevational view thereof.

FIG. 4 is a top plan view thereof.

FIG. 5 is a left-side elevational view thereof.

FIG. 6 is a rear elevational view thereof; and,

FIG. 7 is a bottom plan view thereof.

The broken line shown is for illustrative purposes only and forms no part of the claimed design.
